UNITED STATES PATENT OFFICE.

ALBERT O. ROOD, OF NEW YORK, N. Y., ASSIGNOR TO VINCENT P. TRAVERS,
OF SAME PLACE.

ART OF MAKING HAMMOCKS.

SPECIFICATION forming part of Letters Patent No. 296,627, dated April 8, 1884.

Application filed October 31, 1883. (No model.)

To all whom it may concern:

Be it known that I, ALBERT O. Rood, a resident of New York, in the county of New York and State of New York, have invented 5 an Improvement in the Art of Making Hammocks, of which the following is a full, clear, and exact description, reference being made to the accompanying drawings, in which—

Figure 1 is a top view of my improved hammock, showing one end completed and the other partly completed. Figs. 2 and 3 are diagrams showing the mode of making the ends of the hammock.

This invention has for its object to improve 15 the art of making hammocks, and particularly the ends thereof, so as to render the same more durable, and also more economical in manufacture.

Heretofore the ends of hammocks, which are 20 the parts that connect with the suspension-ropes, were made of separate cords in such a manner that the loose end of each piece of cord had to be carried, with the assistance of a needle, through the eyes in the hammock 25 as far as such piece would extend, and then another piece had to be taken and tied to that previously inserted, and so forth, thus causing much waste of material and involving great loss of time. By my invention I am 30 enabled to form the end loops of the hammock of a continuous thread or cord, taking it from a ball or hank without requiring any part of it to be detached from such ball or hank until the complete end structure shall have been 35 finished.

In making the hammock ends I proceed as follows: Assuming the body A of the hammock, which is shown in Fig. 1, and its selvage B to have been first finished in any known manner, 40 so as to form the eyes a a at each end of the body A, (such eyes a a being represented also in the diagrams Figs. 2 and 3,) I place this body, so finished, on a platform, C, which has two pins, d and f, projecting vertically from it near each end, as shown in Fig. 1. I then take the loose end of a ball of twine or cord, D, and tie it to the pin f, then draw it, as at t, to the first eye a, then double the cord and draw the doubled part through said first eye

a, which is nearest the pin f, as is indicated 50 in Fig. 2, and the looped part g of the double cord, which has thus been drawn through the eye a, is then placed around the pins d and f, in the manner indicated in Fig. 3. I then take the cord loosely from the ball, place it once 55 more around the pin f in single strand, as shown at h in Fig. 3, and then double it again, drawing the doubled part i through the next eye a. I then place this loop i also over the pins d f. The cord is then laid singly around the pins 60 d and f, and is then taken from f to the next eye a, all as indicated by the line j in Fig. 3, and is then doubled, forming the loop m, which is next introduced through the third eye a. Then this loop m is laid over the pins d and f. 65 Thereupon the cord is again laid singly around the pins d f, as shown at o, Fig. 1, doubled, passed through the fourth eye a, as shown at r, Fig. 1, and is then proceeded with in the same manner until all the eyes a have been 70 engaged. When the last eye, a², on the hammock is reached, the same method of connection is pursued, with the exception that the looped cord n at this place is inserted through said eye a² from the opposite side—that is to 75 say, in the lower part of Fig. 1 this loop n is shown to be introduced through the eye a² from the left-hand side, while all the other loops, g, i, m, and r, &c., were introduced through their respective eyes from the right-hand side. I finally, when this has been accomplished, tie the free end p (see Fig. 1) of the cord, which is now cut off from the ball, to the first end of the cord that was tied to the pin f, and slip the cord and its several 80 loops off the pins d and f, whereupon I bind the outer ends of this looped end structure to form the terminal eye s, which is shown at the upper part of Fig. 1. Each end of the hammock is treated in the same manner.

It will be perceived that by this process I am enabled to draw continuously for each end of the hammock from the ball of twine or cord without requiring any part of the cord to be cut until the complete end structure has been 95 finished; and it will likewise be perceived that by this construction I engage each eye a of the hammock with a doubled thread or cord

for the end loops. I find by experience that this construction can be more rapidly and economically carried into effect than any previously-known manner of forming the end loops.

I claim—

The art of making a hammock, which consists in forming the body with the eyes *a* in the ends thereof in any known manner, then forming each end of the hammock by doubling a cord and passing and drawing it through one of the eyes *a* of the hammock-body, then forming the loop *g*, then doubling the cord again and introducing it through another eye

a of the hammock-body, then forming the 15 loop *m*, then passing said loop *m* through the third eye *a* of the hammock-body, and continuing in this manner until all the eyes *a* at the end of the hammock-body have been engaged with the loops formed by the doubled 20 cord, tying the ends of the cord, and, finally, binding the outer ends of this looped structure and forming the terminal eye *s*, substantially as described.

ALBERT O. ROOD.
